UNITED STATES PATENT OFFICE.

THOMAS B. FREAS, OF NEW YORK, N. Y., ASSIGNEE TO THE THERMO ELECTRIC INSTRUMENT COMPANY, OF NEWARK, NEW JERSEY, A CORPORATION OF NEW JERSEY.

MERCURY-TUBE SWITCH.

1,118,900.

Specification of Letters Patent. Patented Nov. 24, 1914.

Application filed January 4, 1912. Serial No. 669,344.

To all whom it may concern:

Be it known that I, THOMAS B. FREAS, a citizen of the United States, residing at New York, in the county of New York and State of New York, have invented a certain new and useful Improvement in Mercury-Tube Switches, of which the following is a specification.

My invention relates to mercury tube switches for use, for example, in connection with constant temperature baths of the general type illustrated in my issued Patent Number 999,710, granted August 1, 1911, and in my pending application, filed December 4, 1911. Serial Number 663,951.

My present invention is concerned more particularly with certain details of construction, for example, the method of mounting the contact needle in the mercury, the construction of the mercury tube itself with its filler duct, and certain other details which will be hereinafter more particularly described and claimed.

In the form illustrated in the accompanying drawings: Figure 1 is a central vertical section of the mercury tube. Fig. 2 is a plan view taken on the line 2-2, Fig. 1. Fig. 3 is a fragmentary section taken on the line 2-2, Fig. 2. Fig. 4 is a section taken on the line 4-4, Fig. 2.

Similar numerals refer to similar parts throughout the several views.

The body of the tube consists of a vertical portion 37 having a horizontal foot or extension at its lower end (not shown). At the upper end of the body portion the tube is contracted in the ordinary manner, forming an orifice 39 above which is an extension 40. The mercury is rendered electrically alive by a conductor 42 passing through a duct 43 leading out of the side of the tube body. The needle 45 which constitutes the terminal with which the conductor 42 is to be electrically connected by the rise of the mercury descends to or near the orifice 39. It will be understood that in order to render the mercury tube very sensitive and to cause the mercury to make and break connection with the needle upon very slight changes of temperature it is necessary that the needle point should come as precisely as possible into the middle of this orifice. In prior constructions it has been difficult, if not impossible, to accurately adjust the needle and bring the point thereof at the

proper elevation and lateral position. The means whereby this is accomplished constitutes one of the novel characteristics of my apparatus.

The needle 45 above mentioned is mounted at the lower end of a rod 46 having a ball 47 near its upper end, the ball being surrounded by an extension 48 preferably of insulating material provided with a handle 49. The rod and ball are conductive, while the handle 49 is insulated from them, or may itself be made of insulating material. Ball 47 rests in a central depression formed in a cap 51 of conductive material which screws onto a bushing 52 supported by the insulating plate 53. Bushing 52 circumferentially incloses the extension 40 of the mercury tube, and by preference a tight connection is made by the introduction of cement or other suitable material 54 between them. Cap 51 is insulated from surrounding objects by means of an outer cap 56 of insulating material which extends above the top of cap 51 and surrounds ball 47. Cap 56 is interiorly threaded and receives the screw bushing 57 centrally apertured to receive the extension 48. Bushing 57 is also made of insulating material. It will be observed that as a result of this construction the needle and its supporting rod are pivotally supported from the ball 47 as a center.

As the parts surrounding the ball permit play the needle may be swung laterally to the center of the orifice 39 and may be set in central position by screwing down the bushing 57. Thus to make a lateral adjustment of the needle point all that is necessary is to back off the bushing 57 slightly so as to permit the ball to rotate a trifle in its bearings and thus retighten the bushing, whereupon the needle will be firmly set. The needle may be elevated or lowered by screwing the cap 51 up or down in the stationary bushing 52. Bushing 52 is rendered electrically alive by a screw 60 mounted in plate 53 and having its inner end touching said bushing, as shown in section in Fig. 3 and in dotted lines in Fig. 2. Said screw forms a binding post in electric connection with the conductor 61, shown in Figs. 2 and 3. Conductors 42 and 61 are connected to the exterior conductors in any suitable manner, preferably as shown in Fig. 4, wherein the ends of the conductors 42 and 61

61 are electrically connected to tubes 62 and 63 respectively by passing up through plate 53 and connected with the conductors 64 and 65 respectively; the connections being protected by housings 66.

A filler tube 70, best shown in Fig. 1, is supported in plate 53 and extends into the body 37 of the mercury tube and down to the foot 38. By this arrangement the mercury tube may be readily filled without the introduction of air bubbles which are frequently the source of annoyance in devices of this class. Here the mercury is conveyed down into the foot where it flows horizontally in such manner as to permit the escape of air as the mercury runs in.

Having thus described my invention, what I claim as new and desire to secure by Letters Patent is:

20 1. In combination, a mercury tube, a needle supported near the upper end of said tube and having its point free to swing laterally within said tube, and means for adjusting the point of the needle laterally within the tube.

2. In combination, a mercury tube, a cap at one end thereof, and a needle passing through an aperture in said cap and having a ball resting upon said cap whereby the 30 needle is pendant and free to be swung laterally, and means for clamping said ball in desired position against said cap.

3. In combination, a mercury tube, a metallic cap at the upper end of said tube,

a needle passing through an aperture in 35 said cap, and having a ball resting upon said cap, and a bushing making screw connection with said cap for clamping said ball.

4. In combination, a mercury tube, a metallic sleeve at the upper end of said tube, a metallic cap screwing onto said sleeve whereby it is vertically adjustable, a needle in said mercury tube passing up through said sleeve and through an aperture in said 45 cap, a ball supporting said needle and resting upon the apertured portion of said cap, an insulated cap fitting over said metallic cap, and an insulating bushing screwing into said insulated cap down onto 50 said ball for holding it and the needle set in proper position.

5. In combination, a mercury tube, a vertically adjustable centrally apertured cap at the upper end of said tube, a ball resting upon said cap at the central aperture therein, a needle suspended from said ball, a handle extending upward from the ball, and an axially apertured bushing surrounding said handle, and adapted to engage said 60 ball for securing it in the position required.

In witness whereof, I have hereunto subscribed my name in the presence of two witnesses.

THOMAS B. FREAS.
